UNITED STATES PATENT OFFICE.

HORACE H. CHITTENDEN, OF NEW HAVEN, CONNECTICUT, ASSIGNOR TO
FOY, HARMON & CHADWICK, OF SAME PLACE.

DESIGN FOR A CORSET.

SPECIFICATION forming part of Design No. 17,049, dated January 4, 1887.

Application filed November 23, 1886. Serial No. 219,727. Term of patent 14 years.

To all whom it may concern:

Be it known that I, HORACE H. CHITTENDEN, of New Haven, in the county of New Haven and State of Connecticut, have invented a new Design for Corsets; and I do hereby declare the following, when taken in connection with accompanying drawing and the letters of reference marked thereon, to be a full, clear, and exact description of the same, and which said drawing constitutes part of this specification, and represents a side view of a corset, showing the design of the hip-section.

This invention relates to a design for corsets, having special reference to the side of the corset.

In the illustration, A represents the rear section, and B the front section, the intermediate portion being the side or hip section. On the surface of the hip-section, and at its lower part, is the representation of a segment-shaped band, starting from the rear edge of the hip-section near the bottom and running upward over and down to near the bottom of the front edge of the hip-section. Near the front edge of the hip-section is the representation of a vertical band, D, represented as extended

from top to bottom, and over the band C, at the rear edge of the hip-section, is the representation of a like band, E, extending from top to bottom, and represented as overlapping the band C. On the bands C, D, and E is the representation of several lines parallel with the edges of the respective bands; but these lines may be varied or omitted without departing from the design.

The shape or ornamentation of the front and rear sections is immaterial to this design.

I claim—

In a design for a corset, the representation upon the sides of a band, C, as running from the front bottom of the sides, curved upward across the side down to the rear bottom of the side, and the representation of vertical bands D E as running from top to bottom of the side, one near the front and the other at the rear, and appearing to cross the band C near its ends, as shown in the accompanying illustration.

HORACE H. CHITTENDEN.
